SOUND RECORDING AND REPRODUCING

Glenn L. Dimmick, Erlton, N. J., assignor to Radio Corporation of America, a corporation of Delaware

Application February 27, 1937, Serial No. 128,072

8 Claims. (Cl. 179—100.3)

This invention relates to an improvement in a method of and an apparatus for recording and reproducing sound, and, more particularly, involving the recording and reproduction of sound on film. The purpose of the invention is to provide improved response at low frequencies and at the same time to reduce ground noise.

It has heretofore been proposed, as is described and claimed in Karolus Patents 1,901,033 and 1,901,034, issued March 14, 1933, to record and reproduce the high frequency components of sound with a very narrow line of light, omitting the low frequency components from that record. The low frequency components, which do not require such high resolving power, were recorded in a separate record by a much wider beam of light, thereby permitting increased exposure in recording, and in reproducing the low frequencies were reproduced by means of a correspondingly wide beam of light, thereby giving greater photo-cell response. This system had the disadvantage that two separate sound-tracks were required, for which space was not readily available on the ordinary sound picture film.

In the performance of my invention I record both the high and low frequencies by means of a relatively narrow beam of light but with an appropriately low modulation in the low frequencies. In reproducing sound from this record I then scan the high frequencies by means of a relatively narrow beam of light having adequate resolving power and scan the low frequencies by means of a relatively wide beam of light coaxial with the narrow beam of light but which, due to its width, picks up relatively less ground noise from the film.

My reproducing apparatus is further so constructed as to permit the selective reproduction of my improved sound record or ordinary variable density or variable area sound records or push-pull sound records, the apparatus being set for either type of record by merely turning a switch.

One object of my invention is to provide an improved sound record.

Another object of my invention is to provide an improved method of recording sound.

Another object of my invention is to provide an improved method of reproducing sound.

Another object of my invention is to provide an improved sound reproducing apparatus.

Another object of my invention is to provide sound reproducing apparatus having an improved frequency response.

Another object of my invention is to provide

sound reproducing apparatus producing a minimum of ground noise.

Another object of my invention is to provide a sound reproducing apparatus readily adaptable to the reproduction of any commercial type of sound record.

Other and incidental objects of my invention will be apparent to those skilled in the art from a reading of the following specification and an inspection of the accompanying drawings, in which:

Figure 1 is a diagrammatic illustration of a sound reproducer made in accordance with my invention, together with a schematic diagram of the output circuit therefor.

Figure 2 is a detail of the sound reproducing apparatus.

Figure 3 is a diagrammatic illustration of the manner in which the coaxial light beams scan the sound record, and

Figure 4 illustrates the frequency characteristics of the sound record and of the reproducing apparatus.

Referring first to Fig. 1, the customary exciter lamp 10 is provided for illuminating the portion of the sound record to be reproduced. An optical system 11 is provided of the customary optical-slit type which illuminates a transverse line on the sound track on the film 12 of a width corresponding to the resolution of the lowest frequencies, i. e., the width of the line of light on the sound track is not more than one-half of the wave length of the higher end of the low frequency band to be reproduced. A lens system 13 is provided which, operating in accordance with Berglund Patent No. 1,564,509, issued December 8, 1925, directs an image of the sound track from the film 12 onto the member 14.

This member 14 is provided with a narrow slit 15, as in the said Berglund patent, through which light is transmitted to the cathode 16 of a photocell 17. This slit 15 is made of a width corresponding to not more than half the wave length of the image of the highest frequency sound waves which are to be reproduced, and these high frequency sound waves are, accordingly, picked up by the cathode 16 and converted into electrical energy which is fed into the primary winding 18 of a transformer,

the secondary 19 of which feeds the current to an appropriate amplifier or other output device. A high-pass filter 9 may be inserted in the circuit if desired.

The member 14 has a mirror surface and the portion of the light beam focused thereon by the lens system 13, but which is not transmitted by

55

50

45

40

the slit 15, is reflected to the mirror 20 which in turn directs it on the cathode 21 of the photocell. Due to the width of this beam of light it is not properly responsive to high frequencies nor to 5 much ground noise, but due to the quantity of light transmitted a high degree of modulation is secured on the lower frequencies. These low frequency impulses are transmitted through the filter 22 (which diagrammatically illustrates any 10 desired type of low pass filter) which serves to eliminate any residual high frequency, photocell hiss or ground noise from the current fed to the transformer primary 23 which feeds current through the transformer to the secondary 19 in 15 the same manner as does the primary 18.

It will be apparent from the foregoing description that high frequencies are reproduced through the cathode 16 and the lower frequencies through the cathode 21 and these are fed in proper 20 phase relation into the transformer from which they are taken off by the winding 19. The frequency characteristic of this reproducing apparatus is illustrated by the curve 30, Fig. 4, showing that the apparatus has a very high response 25 at frequencies up to a few hundred cycles per second, falling off at a frequency determined by the width of the scanning beam on the film 12 and having a considerably lower response at the high frequency end which is scanned by 30 the slit 15. In recording, therefore, it is necessary to provide a record having a frequency characteristic corresponding to the curve 31, which may be readily accomplished by the use of appropriate high pass filters in the recording amplifier, and which has a very high amplitude as 35 indicated at 32 in the higher frequencies. In this type of record, since the amplitude of a modulation of the high frequencies is relatively very high, the ratio of sound to ground noise is 40 correspondingly high in these frequencies, while at the lower frequencies the ground noise is not reproduced by the apparatus and the modulation can be correspondingly low. In the reproduction of a sound record according to the curve 31 45 by means of my apparatus having a response characteristic corresponding to the curve 30 a substantially flat overall response is obtained.

The relation of a low frequency sound wave to my scanning beam is illustrated diagrammatically in Fig. 3 where 15' indicates the area covered by the scanning slit 15, 11' indicates the area scanned by the optical system 11, and 12' shows a variable area sound record as it might appear on the film 12. It will be apparent that 50 the beam 11' can adequately scan the low frequency waves indicated and at the same time produces a very large response, while the beam 15' which is capable of scanning the higher frequencies does not transmit as much light.

60 In order to render the apparatus generally useful, and not limit its usage to the specific type of record just described, I provide the circuit shown in Fig. 1 with an appropriate changeover switch for shifting the device to any desired 65 type of record.

This changeover switch includes three three-way switches with a single actuating means therefor as indicated in Fig. 1, and serves to so change the circuits as to permit selectively the 70 use of either my improved circuit or an appropriate circuit for pushpull records or a circuit for standard film, as described and claimed in Belar application, Serial No. 52,458, filed December 2, 1935, one form of which is illustrated in 75 Fig. 1. In the left hand position of the switch

blade 24 the upper end of transformer winding 23 is connected to the battery 27 while the lower end of the winding 23 is connected through the blade 25 to the cathode 21 through the filter circuit 22. The winding 23 is therefore operating in the same direction as the winding 18 and in accordance with my improved method above described. In the middle position of the blades 24 and 25, the cathode 21 is connected to the upper end of the winding 23 omitting the filter circuit 22 and the lower end of winding 23 is connected to the battery 27, thereby permitting the two cathodes to operate in pushpull relation. In the third position of these switches, the cathode 21 is again connected to the winding 23 as in the first position, but the filter circuit 22 is omitted and the apparatus is then in condition to reproduce ordinary sound records.

The switch blade 26 is used to control the slit plate shown in detail in Fig. 2. This slit plate has the reflecting surface 14 and the slit 15 as described in connection with Fig. 1 and as shown in operative position in Fig. 2. This slit plate is carried in appropriate frame 33 slidable in a second frame 34 and provided with stop rods 35 and 36 to the latter of which it is connected by the rod 37. A spring catch 38 is provided for retaining the frame 33 in either of two positions. In the position shown, light passes through the slit 15 to the cathode 16 and another portion of the beam is reflected from the surface 14 to the cathode 21 as before described. When, however, the frame 33 is moved toward the left in Fig. 2 the other half of the apparatus comes into use and in this portion of the apparatus non-reflecting surfaces 39 and 40 are provided on opposite sides of the slit 41, which permits light from one-half of the soundtrack to pass through the slit 41 to the cathode 16. This slit 41 extends only one-half of the length of 40 the surfaces 39 and 40 and the other half of their length a narrow mirror 42 is provided. This mirror has a width corresponding to that of the slit 41 and reflects a correspondingly narrow line of light to the mirror 20 whence it is 45 reflected to the cathode 21. It will be apparent that when the non-reflecting portion of the slit plate 39 and 40 is in operating position light from one-half of the sound track will be reflected from the mirror 42 while light from the other half is transmitted through the slit 41, thus causing each cathode to respond to the impulses of only one-half of the soundtrack.

The frame 33 is connected by a rod 43 with an armature 44 adapted to slide back and forth in 55 the windings 45 and 46. When the winding 45 is energized the frame 33 is moved to the left of Fig. 2, thus bringing the right hand portion of the device into use; and when again the solenoid 46 is energized, the slit 15 and mirror 14 60 are again brought into use. These solenoids are actuated from an appropriate source of power 47, Fig. 1, by the switch 26, which is interconnected with the switches 24 and 25. It will be apparent that the narrow scanning slit and 65 mirror are used both in pushpull reproduction and in the reproduction of ordinary film, while the mirror 14 is automatically shifted into place for reproduction according to my improved method.

70 It will be apparent to those skilled in the art that my invention is not limited to the specific embodiment thereof shown in the drawings but that this may be considerably modified. For example, it is sometimes desirable to reproduce 75

5 sounds of low frequency by means of one loud-speaker or set of loudspeakers and to reproduce the sounds of high frequency by means of another speaker or set of speakers. In such cases, 10 there is occasionally difficulty due to phase differences between the high and low frequency sounds and I can compensate for this by slightly moving the image 11' produced by the optical system 11 in relation to the slit 15 and this may 15 be accomplished either by moving the optical system 11, the optical system 13 or the mirror 14. Likewise, if I so desire I may transmit the high and low frequencies through separate amplifiers, or even through separate amplifiers to separate 20 loudspeakers.

Having now described my invention, I claim:

1. The method of sound reproduction comprising the steps of scanning an image of the sound track in a narrow line to reproduce high 20 frequencies and simultaneously scanning an image of the same sound track area in a wider line to reproduce low frequencies.

2. The method of sound reproduction comprising the steps of scanning an image of the sound track in a narrow line to reproduce high frequencies and simultaneously scanning an image of the same sound track area in a wider line to reproduce low frequencies, and adjusting the relative 25 position of said lines to determine the phase relation of the reproduced sounds.

3. Apparatus of the class described comprising means for illuminating a sound track with a relatively wide line of light for reproducing low frequencies, and means for selecting a narrow 30 portion of the illuminated area for reproducing high frequencies.

4. Apparatus of the class described comprising means for illuminating a sound track with a relatively wide line of light for reproducing low frequencies, means for selecting a narrow portion of the illuminated area for reproducing high frequencies, means for directing light from said narrow area to one photoelectric device, and means for directing light from said illuminated 40 area to another photoelectric device.

45 5. Apparatus of the class described comprising means for illuminating a sound track with a relatively wide line of light for reproducing low frequencies, means for selecting a narrow portion

of the illuminated area for reproducing high frequencies, means for directing light from said narrow area to one photoelectric device, and means for directing light from said illuminated area to another photoelectric device, said photoelectric devices being connected to a common 5 output circuit.

6. Apparatus of the class described comprising means for illuminating a sound track with a relatively wide line of light for reproducing low frequencies, means for selecting a narrow portion of the illuminated area for reproducing high 10 frequencies, means for directing light from said narrow area to one photoelectric device, and means for directing light from said illuminated area to another photoelectric device, the first of 15 said photoelectric devices being connected directly to an output circuit and the second of said photoelectric devices being connected to the output circuit through a low pass filter.

7. Apparatus of the class described comprising means for illuminating a sound track with a relatively wide line of light for reproducing low frequencies, means for selecting a narrow portion of the illuminated area for reproducing high 20 frequencies, means for directing light from said narrow area to one photoelectric device, and means for directing light from said illuminated area to another photoelectric device, the first of 25 said photoelectric devices being connected to an output circuit through a high-pass filter and the second of said photo-electric devices being connected to the output circuit through a low pass filter.

8. Apparatus of the class described comprising means for illuminating a sound track with a relatively wide line of light for reproducing low frequencies, means for selecting a narrow portion of the illuminated area for reproducing high frequencies, means for directing light from said narrow area to one photoelectric device, means for directing light from said illuminated area to another photoelectric device, said photoelectric devices being connected to a common output circuit, and means for selectively connecting said 35 photoelectric devices to the said output circuit 40 either in tandem relation or in pushpull relation.

GLENN L. DIMMICK.
